HUMIDIFIER AND DUST COLLECTOR

Filed Jan. 3, 1928

UNITED STATES PATENT OFFICE

ROBERT CLIFFORD BENDER, OF DAVENPORT, IOWA

HUMIDIFIER AND DUST COLLECTOR

Application filed January 3, 1928. Serial No. 244,319.

The present invention pertains to improvements in the structures shown, described and claimed in my prior copending applications, more specific reference to which is not considered necessary in the present application. This device, as is readily apparent, pertains to air filtering and humidifying means for use in conjunction with warmed air heating plants. Among the objects of the present invention are to simplify the construction of such a device; to simplify manufacturing operations and cheapen the cost of production of a device of the character indicated; to provide a device in which a greater volume of air may be passed through the air filter; to reduce the lateral discharge below the humidifier; to increase the perforated area for the passage of air; to improve upon dust filters for use in a device of the character indicated; to so shape the parts of a structure of the character indicated that, so far as possible, like parts are interchangeable; to improve upon the means for increasing the evaporation of water; to make the filter screens more readily detachable so that they can be taken out and cleaned; to provide an improved means for attaching a humidifier of the character indicated to a register; and such further objects, advantages and capabilities as will hereafter appear and as are inherent in the construction disclosed.

In the drawing annexed hereto and forming a part hereof, Fig. 1 is a front elevation, in dotted outline, of a warmed air wall register with my improved humidifier shown in place thereon, partly in elevation and partly in section and broken away; Fig. 2 is an end elevation and Fig. 3 is a cross section of my improved structure; Fig. 4 is an elevation of an improved clamping means for attaching the device to a warmed air register.

Referring more in detail to the drawing, numeral 1 denotes the inside face of a wall of a room while numeral 2 denotes a register in this wall. Secured to this register is an

outer container 3 within which is located an inner liquid container 4. A cross bar 5 slotted as indicated at 6 for purposes of adjustment is secured to the register by means of clamps 7 and 8 provided with wing nuts 50. The cross bar 5 has arms 10 turned substantially at a right angle thereto, said arms being perforated for the reception of bolts 11 having nuts upon their inner ends by means of which the arms 10 can be clamped 55 to the brackets 12 to prevent rotation thereof about the bolts as pivots. The upper ends of these brackets 12 are slotted at 13 as indicated in dotted outline in Figs. 2 and 3 for the reception of clamping bolts 14 having 60 nuts by which the same can be tightened up. The bolts 14 pass through the lower extremities of the ends 15 of the outer container, which ends are perforated as indicated at 16 for the passage of air rising from the register 65 to the inside of the container. These ends are covered by screens 17 preferably consisting of a layer of wire netting 18 covered on the inside by a layer of fine mesh cloth 19. The ends of the outer container are perforated 70 and have the metal bent inwardly at an angle as indicated at 20 to form a support for the lower edge 21 of the filter 18, 19. Other perforations are formed in the ends and have the metal bent outwardly to form ears 22 for 75 the support of the arms 23 forming a part of the air deflector 24. One end of each arm is bent upwardly as indicated at 25 to prevent the deflector from being accidentally detached from the casing. To cooperate with 80 the other lug 22 the arm is bent upwardly slightly as shown in Fig. 2. Wing plates 26 fit under the deflector 24 and against the ends of the outer casing, being held in place thereon by the bolts 14 by means of which 85 the brackets 12 are clamped to the casing. These wing plates are not considered necessary except in cases where a great deal of soot and dirt rise from the furnace through 90 the register. In such cases, the wing plates 95

will help to prevent the rising current of air and dust from passing outwardly around the ends of the container, forcing the same to pass upwardly therethrough and through the screens lining the container. The wing plates have an edge bent over at 26^a to form inward extensions 27. These extensions or flanges rest against the back of the outer container.

- 10 The presence of the slots 6 in the cross bar 5 renders it possible to adjust the humidifier and dust collector transversely with respect to the register so that the same will be properly positioned laterally with relation thereto.
- 15 The slots 13 enable the humidifier to be adjusted vertically so that the bottom portion of the outer container will have the proper position with respect to the top of the register. Perforations 30 and 31 in the body, cover and deflector permit the escape of the air currents from which the dust and dirt have been removed. The increase in the perforated area reduces the obstruction to the passage of filtered air and therefore makes it possible for a greater amount thereof to pass through the filter and humidifier.
- 20
- 25

At 32 and 33 are shown portions of the upper edge of the end walls turned down to serve as holding means for the filters 18, 19. 30 The central portion of these upper edges of the end walls are turned in horizontally, as indicated at 34, to form supports for the inner container which has the upper edges of its ends turned outwardly as shown in 35 Fig. 1 at 35 to form cooperating flanges which rest upon the projections 34 and thus support the inner container in position in the outer container. Within the inner container is a sheet of absorbent fabric 36 which is held 40 against the front and back walls of this container by a flexible wire netting 37.

43 The present construction differs in one particular from one of my prior constructions in dispensing with the central chimney through which the heated air rose to cause evaporation of the liquid in the container. That construction was much more expensive to manufacture than the present construction and had less heated area against which the fabric was held. In the present instance, the fabric is held tightly against the inside of the walls of the container and the heated air passes along these walls and causes evaporation of the liquid which rises by capillary force in the wicking.

Filters 40, 41, 42 and 43, similar in construction to the filters 18, 19, are placed, respectively, inside of the ends of the cover, within the cover, within the front face of the body of the outside container and back of the deflector 24. The action of the filter 41 is considerably improved by spacing the same from the inner face of the cover 44, thus leaving a chamber between the filter and the cover in which the air has free circulation.

This filter is readily detached from the cover by slipping one edge out past the inwardly projecting flange of one of the brackets 45 secured on the inner face of the cover. These brackets 45 may, if desired, be in the form of angles extending substantially throughout the length of the cover, but it is preferred to take short pieces of angle stock and fasten them adjacent opposite ends of the cover. If it be found desirable to do so, an additional bracket 45 may be placed substantially midway of the length of the cover. The lower edge of the front face of the outer container is bent inwardly and upwardly as indicated at 46 to form a pocket into which the lower edge of the air filter 43 may be inserted. A similar pocket is provided in the upper edge of this member. The upper edge of deflector 24 is turned inwardly and downwardly as indicated at 47 to form a pocket for the reception of the edge of air filter 42. Suitable means 48 may be provided at the lower edge of the deflector 24, either by securing angular brackets thereto or by bending the lower edge of the deflector or portions thereof inwardly to form the necessary retaining projection. From what has been said above, it will be apparent that the air filters may be readily removed to be cleaned and be then returned to their proper positions to function as before. Because of the changes in construction the cleaning of the filters is made much easier than in prior constructions. Since the screens are readily interchangeable screens of different finenesses may be used as desired under different conditions.

The ends of the cover are made interchangeable so that in fabricating the cover it is not necessary to select right and left parts but two identical parts may be selected at random and applied to the formed body portion 49 of the cover 44, the parts being quickly secured in place to complete the rigid part of the cover. After this has been done, the filters 40 and 41 are inserted and the cover is completed. The two ends of the inner container, as well as the two ends of the outer container, are made interchangeable so that a single die is needed for each, instead of two dies, and assembly operations are made more rapid and less expensive. Attention is also called to the fact that the screens which occur in pairs are made interchangeable and screen 41 may be put into the cover either side foremost. Also, the brackets 12 are made identical so that there is no choice in selecting these for purposes of assembly. Both the cover 44 and the inner container are reversible, thus tending to simplification of assembly operations. Bars are secured exteriorly of the ends of the liquid container 4, said bars having their ends 50 and 51 extending beyond the sides of the liquid container in order to properly space the inner container from the front and back walls of

the outer container. It will of course be understood that these cross bars may be omitted if desired as the inner containers can not be spaced very much out of the way, whether they are provided with the spacing means 50, 51, or not.

Having properly positioned the bar 5 upon the register and having tightened up the nuts 9 to hold the same in place, the outer container is attached to the ends 10 of the bar 5 by means of bolts 11 which are tightened up to hold the same properly positioned, after the outer receptacle has been adjusted vertically with respect to the register until the lower edge of the back face thereof overlaps the top of the register slightly as shown in the drawing. With the bolts 11 and 14 all tightened up the device is ready to have the deflector 24 mounted thereon and the inner container inserted. When this has been done liquid, preferably water, is placed in the inner container and the cover 44 is put into position. Heat rising through the register will pass between the inner and outer containers and heat up the walls of the inner container to cause evaporation of the liquid to take place. The warmed air rising between the inner and outer containers is filtered as it passes out through the screens 40, 41, 42, 43 and 18, 19, and is humidified by the water evaporated.

While I have disclosed what is now considered the preferred embodiment of my invention, I desire it understood that this is to be construed as illustrative only and not in a limiting sense.

Having now described my invention, I claim:

1. In a humidifier and dust collector having a flat sided casing for attachment to a hot air register with a flat side toward the register, a liquid container mounted in the casing, said liquid container having an absorbent fabric resting flatwise against the inner faces of some of its walls and means for pressing said fabric against said walls.

2. In a structure of the character described, a flat sided casing adapted to be mounted flat against the front side of and above a hot air register, said casing having perforations in some of its walls and having in its upper part projections extending inwardly to form supporting ledges, and a liquid container positioned inside said casing, said liquid container having ledges extending outwardly to cooperate with the first named ledges in supporting the container in the casing.

3. In a humidifier and dust collector, a casing to be mounted above and in front of a hot air register, said casing being shaped symmetrically with relation to a longitudinal axial plane, a liquid container mounted in said casing, said liquid container being oblong and shaped symmetrical with relation

to a longitudinal vertical plane and having the top edges of its ends turned outwardly to form supporting ledges whereby the container may be suspended in the casing.

4. In a humidifier and dust collector for attachment to a warm air register, a casing open at its bottom, closed at its sides and ends, and provided with a removable top, the ends, front side, and top being perforated for the escape of air therefrom, an air deflector detachably mounted adjacent the bottom of the casing and inclined downwardly and outwardly, and plates substantially closing the space below the casing at the ends thereof and between the register and deflector, the ends, front, top and deflector being perforated for the passage of heated air therethrough and being lined with a previous dust collector for the removal of dust from the air passing therethrough.

5. In a humidifier and dust collector for attachment to a warm air register, a casing open at its bottom, closed at its sides and ends, and provided with a removable top, the end, front side, and top being perforated for the escape of air therefrom, an air deflector detachably mounted adjacent the bottom of the casing and inclined downwardly and outwardly, and plates substantially closing the space below the casing at the ends thereof and between the register and deflector, the ends, front, top and deflector being perforated for the passage of heated air therethrough and being lined with a previous dust collector for the removal of dust from the air passing therethrough, said casing having a liquid container suspended therein by means of end flanges, said liquid container being spaced from the walls of the casing to permit air to have access to all sides thereof.

6. In a humidifier and dust collector for attachment to a warm air register, a casing open at its bottom, closed at its sides and ends, and provided with a removable top, the ends, front side, and top being perforated for the escape of air therefrom, an air deflector detachably mounted adjacent the bottom of the casing and inclined downwardly and outwardly, and plates substantially closing the space below the casing at the ends thereof and between the register and deflector, the casing having projections extending inwardly at the upper edges of its ends to form supporting means for a liquid container, and a liquid container mounted within the casing and provided with projections extending from its ends to cooperate with the projections in the casing in suspending the container within the casing.

7. In an air filter for warm air registers, a straight oblong casing having its bottom open and uncovered during use and its exposed sides perforated for the escape of air passing into the casing, the said casing being

mounted on the register with its small dimension extending away from the wall and having short projections on the interior thereof extending inwardly from its interior faces to detachably support dust collecting fabric mounted on the inside faces of the casting, said fabric being supported in place by said projections and being readily removable by being pulled away from the supports.

10 In witness whereof, I hereunto subscribe my name to this specification.

ROBERT C. BENDER.
